[57] CLAIM

The ornamental design for a retention suture bridge, as shown.

DESCRIPTION

FIG. 1 is a front perspective view of a retention suture bridge showing my new design;

FIG. 2 is a top plan view thereof;

FIG. 3 is a right-end elevation view thereof; the left-end elevation view is the same;

FIG. 4 is a front elevation view thereof; the rear elevation view is the same; and

FIG. 5 is a bottom plan view thereof.
